UNITED STATES PATENT OFFICE

EDWARD J. MCKERNAN, OF TOPEKA, KANSAS

BRASS-TRUING MACHINE

Application filed July 6, 1926. Serial No. 120,550.

My invention relates to a machine more especially intended for machining and truing the bearing surface of car brasses employed in the journal bearings of railroad cars.

5 The invention has for its object the provision of a portable hand operated machine constructed to accommodate any size of car brass at present in use; the invention contemplating means whereby the brass is securely held in place on the chuck of the machine and given a true radius, and true, even bearing surface disposed square with the back or non-wearing face of the brass.

10 The objects and advantages of my invention will be more readily comprehended from the detailed description of the accompanying drawings, wherein—

Figure 1 is a side elevation of my improved machine.

15 Figure 2 is a plan view thereof with a portion of the arbor broken away and shown in section.

Figure 3 is a detail vertical sectional view taken on the offset line 3—3 of Figure 1 looking in the direction of the arrows.

20 Figure 4 is a detail view taken substantially on the line 4—4 of Figure 1 illustrating a portion of the drive and driven elements.

Figure 5 is a detail sectional view of the 25 operating mechanism at the right hand end of the arbor and feed screw as illustrated in Figure 1.

Figure 6 is a detail perspective view of a feed-nut.

30 In the particular exemplification of the invention, the machine consists of the two end castings or standards 10, 11 connected together by the longitudinal frame members 12, 12 which in turn provide suitable support for a chuck-box indicated generally at 13, the upper out-turned ends whereof are secured to the frame members 12 by means of bolts

35 14. The chuck-box is provided with an adjusting wedge plate or member 15, a liner 16 and a chuck proper or block 17; the latter being provided with the stepped holding surfaces 18, as shown in Figure 3.

40 The liner 16 and the chuck 17 are properly aligned in the chuck-box 13 by means of a suitable bracket or strap 19 which extends about

one end of the chuck-box and is properly secured thereto as for example by bolts 20, see Figures 1 and 2.

At the opposite end of the chuck-box, I provide a bracket 21 which acts as a support for 35 an adjusting screw 22 which is threaded into adjusting wedge 15; the bracket 21 also acts as a stop so that rotation of the screw 22, by means of hand-wheel 23, will cause the wedge plate 15 to travel lengthwise of the screw; 40 longitudinal movement of the screw being prevented by bracket 21. As is apparent from the construction shown, inward or outward movement of the wedge plate 15 will either cause the chuck block 17 to be raised or lowered and thus determine or control the relation of the brass operated on to the cutting mechanism later to be described.

45 After the brass (indicated in dotted lines at A in Figure 3) has been placed on the stepped surface 18 of the chuck 17 (the stepped surface being made to accommodate the chuck to varying sized brasses), the brass is then clamped in place on the chuck by means of the hook members 24, 24 which are 50 adapted to engage with opposite sides of the brass. The lower ends of the hook members 24 are secured to a clevis 25 located transversely beneath the chuck-box and which in turn is provided with a clamp screw 26 provided with handle 27; the clamp screw 26 55 abutting against the bottom of the chuck-box 13. It is evident that upon proper rotation of screw 26 through the medium of handle 27 the hooks 24, 24 through the medium of clevis 25 will be drawn downwardly with the upper ends of the hooks in firm clamping relation with the upper surface of the sides of the brass; the latter being drawn 60 downwardly on the chuck block and held 65 against lateral movement by the stepped surfaces.

70 The upper ends of the standards 10, 11 are apertured to receive an arbor 28; the ends whereof are preferably provided with suitable bushings 29. The arbor extends from end to end of the machine in vertical alignment with the longitudinal center of the chuck, see Figure 3. The tops of the standards 10 and 11 are shown provided with 75

80 85 90 95 100

oil receiving apertures 30, 30 for properly lubricating the arbor. The arbor 28 is provided with a machined slot at 31, extending lengthwise of the arbor, in which a feed screw 32 is located and disposed lengthwise of the machine; the screw 32 extending through opposite ends thereof as shown in Figure 1. The arbor bearing at the end of the machine provided with pedestal or supporting frame 11 is supported by means of an arbor bearing portion 33 formed to slide axially into place and to be secured to the supporting standard 11 by means of suitable bolts as at 34. With this construction, it is apparent that easy assembly of the parts may be had and at the same time replacement and substitution of the cutter-head shown at 35 is readily permitted. When it is desired to change the cutters, the cutter-head 35 (having cutting tools 35^a) is moved along the arbor by means of feed-screw 32, until the cutter-head practically reaches the arbor bearing 33. The end of the feed screw 32, adjacent to arbor bearing 33, is provided with a bearing 36 and with a hand-crank 37 whereby independent rotation of feed-screw 32 may be induced and the cutter-head 35 caused to travel in the manner stated. The bolts 34, which hold the arbor bearing 33 in place on the out-board bearing casting or standard 11, are then removed, thus allowing the arbor bearing 33 to slide axially off arbor 28. The cutter-head or tool holding mechanism 35 may then be removed from the arbor 28 by turning a feed disc 38 located at the right hand end of the arbor.

The cutter-head 35 is provided with a feed-nut 39, shown in detail in Figure 6. The feed-nut 39, as shown, is of an elongated tubular type having end portions or lugs 40, 40 disposed toward one side of the nut and adapted to engage with opposite sides of the cutter-head 35; the feed-nut 39 being threaded to ride on feed-screw 32.

When a different sized cutter-head is to be employed; the feed-nut 39 is removed from the cutter-head and inserted into a cutter-head of a different or desired size and the cutter-head with the feed-nut placed on the end of the arbor 28 and feed-screw 32 and the operations heretofore mentioned in connection with the removal of the cutter-head are then reversed for the purpose of re-assembly.

The feed-screw 32 is supported in the machined slot disposed lengthwise of arbor 28 by means of two disc bearings, disc bearing 36 and a disc bearing 41 at the opposite end. The disc bearing 36 is secured to one end of the arbor 28 for example by means of countersunk head machine screws, not shown; while bearing 41 is preferably made somewhat in the form of a cup, threaded on the cupped side to screw onto the end of arbor 28 and held from turning by means of a screw 41^a.

Power is imparted to the arbor 28, in the particular exemplification of my invention, by

hand-crank 42 secured to a driving gear 43 which latter meshes with a driven gear 44, which latter is secured or keyed to one end of arbor 28. The driving gear 43 rotates on a stub-shaft 45 suitably mounted in the supporting standard 10.

The feed disc 38 keyed or properly secured to the end of feed-screw 32 against independent rotation is provided with a plurality of notches disposed circumferentially equi-distances apart about the periphery of the disc as shown at 46 in Figure 4. These notches are adapted to receive the hook-end 47 of a feed spring 48 which is stationarily secured to the end casting or standard 10 in any suitable manner as for example by the bracket 49. The feed spring 48 is intended to successively enter or engage a notch 46 during each revolution of arbor 28 and thereby induce the feed-nut 39 with the cutter-head 35 to move a predetermined distance along the arbor 28 and position the cutter-head relative to the arcuate surface of the brass so as to induce a cut to be made over the entire journal bearing face of the car brass. The feed spring 48 induces a predetermined degree of rotation of the feed-screw 32 during the successive engagements in the notches 46.

After the cutter-head has moved from one end of the car brass to the other, the mechanism may be reversed so as to bring the cutter-head toward the gear end of the machine by operation of the hand-crank 37 (at the out-board end 11 of the machine) secured to the feed-screw 32. Through operation of the hand-crank 37, the cutter-block 35 with its cutting tools 35^a is repositioned without necessitating a reverse operation of the gear mechanism; the operation of the feed-screw by means of hand-crank 37 inducing a faster return of the cutter mechanism toward the gear side of the machine without necessitating rotation of the cutter block. The ability to return the cutter-head in this manner eliminates any possibility of wear on the cutting tools and therefore at the same time avoids chatter marks being made on the car brass.

The standards 10, 11 are shown secured to or mounted on a suitable platform or base 50, thus enabling the machine to be placed in any desired position, or placed on a small hand truck to be transported about the shop or moved to the place of use.

The machine as illustrated has proven very efficient in practice, but modifications in certain respects are possible and may be made without, however, departing from the spirit of my invention.

What I claim is:

1. In a brass truing machine, a chuck box 125 having upstanding sides whereby the box may be secured to a supporting member, said side walls having vertical slot-ways, the ends of the chuck box being open, a chuck block, the lower surface thereof is tapered, a similarly

tapered wedge block slidable on the bottom of said box and beneath the chuck block, said wedge block having a threaded bore extending longitudinally from one end of the wedge block, a bracket disposed about one of the open ends of the chuck box for preventing lengthwise movement of the chuck block, an adjusting screw extending into the threaded bore of the wedge block, a second bracket 10 disposed at the same end of the chuck box and through which the adjusting screw extends whereby lengthwise movement of the screw is prevented, a pair of upstanding arms disposed in the slots in the sides of the chuck 15 box, having inwardly disposed upper ends above the chuck box, a transversely disposed member beneath the chuck box pivotally connected at its ends to the lower ends of the arms whereby both arms are operatively connected together, and a clamp screw threaded through said last member and engaging the bottom of the chuck box whereby screwing of the clamp screw causes said transversely disposed member to ride lengthwise of the clamp 20 screw and both arms simultaneously moved 25 together.

2. In a brass truing machine, an open ended chuck box having two side walls with vertical slots and terminating at top in supporting flanges, a chuck block provided with a depression on its upper surface having stepped sides to receive brasses of different size, the lower surface of the chuck block being tapered, a tapered wedge block disposed 30 throughout the bottom of the box and slidable beneath the chuck block, means secured to one end of the chuck box whereby lengthwise movement of the wedge block may be induced and its position maintained, a pair of 35 hook members arranged on opposite sides in the slots of the chuck box with their upper hook ends disposed inwardly to engage the upper sides of the brass, a clevis pivotally secured to the lower ends of both hook members, and a clamp screw threaded through the clevis and adapted to engage with the bottom of the chuck box whereby said hook members are drawn downwardly into clamping 40 relation with the brass.

50 EDWARD J. MCKERNAN.
